MINIATURE LAMP INSTRUMENT
ILLUMINATOR SYSTEM

Paul Kollsman, Stamford, Conn.

Application October 15, 1937, Serial No. 169,121

5 Claims. (Cl. 176—32)

This invention relates to electric illuminating means, and especially to a lamp, base and socket combination which is particularly adapted to utilization with an indicating instrument, and 5 to easy removal and replacement of the lamp member from the front of the instrument under difficult operating conditions.

In the illumination of indicating instruments, particularly airplane instruments, it has been 10 found convenient to provide a cover glass or sight glass for the instrument, with white paint or diffusing means at the edge of the glass over most of its periphery, and to provide adjacent one point in the periphery, a very small miniature 15 lamp, which, by radiating into the exposed edge of the glass, delivers light to the diffusing means adjacent the edges of the glass cover plate, from which it is thrown onto the scale graduations and pointer.

20 Great difficulty has, however, been experienced in obtaining a lamp and socket combination which is sufficiently small to avoid interference with the various instruments; which will stay firmly in place in spite of the extreme vibration encountered in airplanes; and which can be readily 25 changed when it burns out, with a minimum of difficulty and a minimum of interference with other instrument parts, and which can be changed easily enough to permit the user to make 30 the change while in flight.

Thus, the problem requires that the lamp shall be extremely small; that it shall be replaceable from the front of the instrument; that it shall be held firmly in place, and that it shall have members which are readily grasped by the operator's 35 fingers to remove and replace the lamp.

The present invention provides a socket, a base cooperating therewith and a miniature lamp held therein, which is readily inserted and removed from the front of the instrument, into 40 illuminating relationship with the edge of the glass sight window of the instrument.

The present invention is an improvement over the instrument shown in Patent No. Re. 20,937, 45 (and is a continuation in part of my applications for patent, Serial No. 719,115 and Serial No. 53,972).

Thus, an object of the invention is to provide for the removable and replaceable mounting of 50 a miniature incandescent electric light bulb in a socket, through the length of which the bulb passes during the removal and replacement.

A further object of the invention is to pass a 55 miniature lamp bulb through the length of a supporting socket and to anchor it therein while making electric connection thereto.

A further object of the invention is to remove and replace a lamp base by manipulation of a finger grip portion while passing the lamp bulb 60 through a supporting socket.

Still another object of the invention is to pass a lamp bulb through a socket member into illuminating relationship with an object and lock the lamp in position by a bayonet joint system. 5

Still a further object of the invention is to pass a lamp bulb through a socket into illuminating position and hold it therein by the interrelationship of contact pins and latch springs.

Yet another object of the invention is to support a lamp bulb in a rectangular base, pass the 10 bulb through a rectangular socket, and lock the rectangular base within the rectangular socket.

Still another object of the invention is to support a lamp in a socket, and make electric contact thereto by means of pairs of rotatable switch 15 blade type of contact-making lock members.

Still another object of the invention is to pass a lamp bulb through a socket, into illuminating position with respect to an instrument dial, to hold the lamp in illuminating position by the 20 application of a locking member, and to eject the lamp from the socket by a contact spring upon removal of the locking member.

Still a further object of the invention is to pass a lamp bulb through a socket, lock it therein, and 25 make electric contact thereto through a ferrule adjacent one end of the lamp bulb, and a tip contact at the other end of the lamp bulb.

Other objects and structural details will be apparent from the following description when 30 read in connection with the accompanying drawings, wherein

Fig. 1 is a side view, partly in section, of a 35 lamp, a lamp base, and socket combination utilizing a bayonet joint type of lock;

Fig. 2 is a top view of the socket of the embodiment of Fig. 1;

Fig. 3 is a bottom view of the lamp and base members of the embodiment of Fig. 1;

Fig. 4 is a detailed view of the locking members of the socket of Fig. 1;

Fig. 5 is a side view, partly in section, of a 45 socket, lamp and lamp base combination utilizing spring grip members for holding the lamp and lamp base therein and making electric connection thereto;

Fig. 6 is a top view of the socket member of the embodiment of Fig. 5;

Fig. 7 is a bottom view of the lamp and base members of the embodiment of Fig. 5;

Fig. 8 is a top view of a square socket utilizing 50 spring clip members;

Fig. 9 is a bottom view of a lamp and square base member adapted to cooperate with the 55 socket of Fig. 8;

Fig. 10 is a side view, in section, of an embodiment utilizing spring switch lock members;

Fig. 11 is a skeleton view of the switch lock members and lamp of the embodiment of Fig. 12;

Fig. 12 is a side view, partly in section, of an 60

alternative form of socket, base and lamp bulb in which the connection to the filament is made between opposite ends of the bulb.

Referring to Figs. 1, 2, 3 and 4, which show 5 a preferred embodiment of the invention, the lamp member 1 is mounted, preferably by cementing or by friction grip or other supporting means as desired, in a tubular insulating material base 2, which has a finger grip portion 3 which 10 may be knurled or smooth, as desired.

The base portion 2 is provided with contact pins 4. The socket member 6 may conveniently be made as part of an airplane instrument case member 5, as shown, and it is desirably positioned 15 at an edge of the instrument, above and adjacent to the sight glass window 7. The window 7 has a cooperating light chamber interposed between the socket and the glass and has adjacent its edge a diffusing medium 8, such as 20 a coating of white paint or a ring of frosted aluminum, in either event the diffusing medium being omitted over a short portion of the glass 7 adjacent the socket 6. Bayonet joint slots 9 in the socket member 6 are provided, adjacent to 25 lock spring members 11 which are connected to the respective electric power supply means.

For airplane instrument service the bulb 1 may conveniently have a diameter of approximately $\frac{1}{8}$ inch, the base portion 2 may conveniently have a diameter of approximately $\frac{1}{4}$ 30 inch, and the finger grip portion 3 may conveniently have a diameter of approximately $\frac{3}{8}$ inch.

In the operation of this device, the lamp member 2 is entered into the socket 6 from the front of the instrument, and then the base portion 2 follows into the socket 6, thereby carrying the bulb member 1 through the socket into illuminating relationship with the edge of the glass 7, the 40 pins 4 being passed down the bayonet slots 9. The finger grip portion 3 is then given a small amount of rotation which carries the pins 4 under the contact locking springs 11, thereby holding the base and lamp firmly in the socket and 45 simultaneously making electric contact for the energization of the lamp filament. As will be obvious, this procedure is readily conducted by an operator wearing heavy gloves in spite of the small size of the members utilized, because of 50 the extreme simplicity of the construction and of the movements required. Thus, this illuminating means cooperates readily with an airplane instrument for the illumination of the dial and pointer thereof to provide a highly efficient lighting system. It is to be noted that 55 the instrument is desirably equipped with a black dial having white graduations and numbers and a white pointer. By this construction, only a minimum of total light flux radiates from the 60 instrument to the observer's eye, and the contrast between the black dial and the illuminated scale and pointer is sufficiently high to make the scale and pointer readily readable without reducing the user's visual acuity when his eyes 65 are dark adapted, as during night flying. In addition, the lamp and socket are extremely small; do not add objectionably to the size of the instrument, and, in addition, the lamp portion 70 is very readily removed and replaced when desired for such reasons as a burned out bulb; and the necessary electric connections are automatically made by the mere operation of inserting the bulb and base into the socket, which operation is conducted wholly from the front or exposed face of the instrument.

Another desirable and preferred embodiment of the invention is shown in Figs. 5, 6 and 7. This embodiment is particularly convenient and desirable because of the fact that it does not require any twisting of the bulb or base during 5 insertion of the lamp. As shown in these figures, a bulb 21 is provided which is attached, preferably by cementing, in a base member 22 which has a finger grip portion 23, and contact pins 24 which are connected by suitable leads to 10 the respective terminals of the lamp filament. The socket member 26 of the combination is preferably formed as part of the instrument case 25, adjacent the sight glass 27, which has a diffusing material 28 at the edges thereof, as in the 15 previously described embodiment. Entrance slots 29 are provided at opposite sides of the socket 26 for the admission of the contact pins 24, and spring members 31 are provided below the entrance slots 29. The spring members have 20 curved tops and locking depressions 32, as shown in Fig. 5, into which the pins 24 enter, and the depressions 32 are shaped to provide a snug grip which is resistant to vibrations, but which will release the pins 24 when a substantial outward 25 pull is applied to the finger grip member 23.

In the first described embodiment the pins 4 may conveniently have flat ends to minimize the space required but in the embodiment of Figs. 5, 30 6 and 7 the pins 24 preferably have rounded ends to make a more satisfactory engagement with the depressions 32 in the springs 31, since a more satisfactory holding and a superior engaging and disengaging action is thereby attained.

In operation, the lamp, bulb and base are 35 inserted into the socket into illuminating relationship with the glass cover plate 27 and the lamp member is passed entirely through the socket into a light chamber adjacent the glass 27 in the same manner as occurs in the previously 40 described embodiment and are held therein by engagement between the springs 31 and pins 24, which simultaneously make the necessary electric contact for supplying power to the filament. Thus, this embodiment performs broadly the 45 same functions as the previously described embodiment, with the additional advantage that no rotation of the base and bulb is required for locking the lamp in place.

Another desirable embodiment is shown in Figs. 50 8 and 9, which embodiment is in general closely similar to the previously described embodiments. A similar lamp 41 is cemented into a base 42, which base is provided with a finger grip portion 43 and locking pins 44, to which electrical connection is made from the respective ends of the 55 filament of the lamp 41. The base member 42 and finger grip portion 43 are square in plan rather than circular as in the previously described embodiments. The socket member 46 is 60 desirably made as an integral part of the instrument case 45, and is also square in form. A sight glass 47 and diffusing medium 48 are provided as in previous instances. Slots 49 are provided for the entrance of the pins 44 and contact 65 springs 51, closely similar to the contact springs 31, are also provided with depressions similar to the depressions 32.

This embodiment operates in a manner closely 70 similar to the second described embodiment with the still further advantage that the base can not be rotated after a partial insertion into the socket. When the base is once inserted, with the pins on the proper sides, the further entry, locking in place, and completing of the electrical 75

connections, occurs without further action other than a straight inward push upon the finger grip portion 43.

Still another desirable embodiment of the invention is shown in Fig. 10 in which a lamp bulb 101 is cemented within a base member 102 which has a finger grip portion 103. Attached to the underside of the base member 102 are spring grip members 104 which are connected respectively to the ends of the filament within the bulb 101. The socket 106 is desirably formed as an integral part of the case member 105 in suitable relationship to the sight glass 107 and the diffusing member 108. Attached within the socket 106 are spring grip members 109, as is particularly well shown in Fig. 11. The members 109 are connected to the respective terminals of the current supply and with the members 104 serve as circuit leads and locking members to hold the lamp in place.

In this embodiment of the invention, the base 102 may be grasped by its finger grip portion 103 and inserted into the socket 106 carrying the bulb 101 into and through the socket into an illuminating relationship with the sight glass 107 and thereafter may be given a partial rotation to engage the free ends of the members 104 under the free ends of the members 109, whereafter the lamp is held firmly in place by the spring grip 20 occurring therebetween. This embodiment provides the advantages of the previously described embodiments, and in addition the further advantage that the lamp and base are very solidly held in place with circuit connecting means 35 which will carry a relatively large amount of current without heating or an undue voltage drop in the contact surfaces.

Still another embodiment of the invention is shown in Fig. 12, in which the lamp bulb 121 is shown mounted in a base member 122 which may be of insulating material which may be threaded, or may be equipped with bayonet type locking pins and may have a finger grip portion 123 attached thereto. A metallic ferrule 124 is provided around the lamp 121 attached to the base member 122 with one terminal of the filament connected thereto. The other terminal of the filament is connected to the tip contact 125 carried upon the outer end of the bulb 121. The socket 126 is desirably made as an integral part of the instrument case as in the previously described embodiments, and is positioned in proper relationship to the sight window glass. Within the socket 126 there is provided a screw thread 127 or bayonet locking slots as before described, adapted to cooperate with the thread or pins upon the base member 122. At the bottom of the socket 126 there is provided a contact member 128 adapted to cooperate with the tip contact 125. The member 128 is connected to one lead of the power circuit. A metal ring member 129 is provided within the socket adapted to cooperate with the metal member 124 and connected to the other terminal of the power supply. In this embodiment also, the lamp 121 is readily inserted through the socket into operative relationship with other instrument members and is held firmly therein to obtain the advantages previously pointed out in connection with the other embodiments and, in addition, to obtain a simplified circuit connection means.

The various embodiments of the invention thus provide simple, relatively inexpensive, illuminat-

ing means for an instrument, particularly adapted to airplane instruments, although adaptable to other instruments as well, in which the lamp bulb is inserted into and through a socket member to bring it into operative relationship with the instrument dial, and simultaneously is insertable by very simple means of such ruggedness and simplicity as to be readily operable under difficult situations.

While there are above disclosed but a limited 10 number of embodiments of the invention, it is possible to produce still other embodiments without departing from the inventive concept herein disclosed, and it is therefore desired that only such limitations be imposed upon the appended 15 claims as are stated therein or required by the prior art.

What is claimed and desired to be protected by United States Letters Patent is:

1. The combination with a lamp socket member having a passage therethrough; of a lamp and base assembly cooperating therewith, said assembly comprising a lamp bulb, a base having a finger grip portion and a pair of symmetrical engaging members attached to said base, the 25 said socket member having interlocking members cooperating with the engaging members on said base to hold said bulb in place and simultaneously to complete an electric circuit thereto.

2. The combination with a lamp socket structure including a tubular passage having bayonet joint slots therein; of a lamp and base combination structure cooperating therewith comprising a lamp bulb passable through said passage into said socket into illuminating relationship 35 with a part to be illuminated; a base member attached to said bulb and enterable into said socket; said base member having a finger grip portion positioned outside of said socket; pin members attached to said base and positioned 40 cooperatively with the bayonet slots in said socket; and resilient contacts within said socket contacting with said pins.

3. In combination, a lamp socket member having a rectangular passage therethrough; a rectangular base member enterable therein, said base member having a finger grip portion remaining outside said passage; a lamp bulb attached to said base member; and pin members and locking spring members cooperating between 50 said socket and said base member for holding said base within said socket.

4. In combination, a lamp socket member having a passage therethrough; a lamp bulb passable through said socket; a base for said lamp bulb 55 attached thereto and having a finger grip portion; and spring members within said socket rotatively engageable with said base for making connection to said bulb, and simultaneously holding said base in place.

5. In combination, a lamp socket member having a passage therethrough; a lamp bulb passable through said socket; a base for said lamp bulb attached thereto and having a finger grip portion; and spring members within said socket rotatively engaging with said base for making connection to said bulb and simultaneously holding said base in place, the said springs comprising a pair of arcuate members attached within said socket and a matching pair of arcuate members 70 attached to said base.

PAUL KOLLMAN.
